(57) **CLAIM**

We claim the ornamental design for medical tensioning device, as shown and described in the drawings.

DESCRIPTION

FIG. 1 is a perspective top view of a medical tensioning device in accordance with the new design;

FIG. 2 is a side elevational view of the medical tensioning device of FIG. 1;

FIG. 3 is an opposite side view of the medical tensioning device of FIG. 1;

FIG. 4 is an end elevational view of the medical tensioning device of FIG. 1;

FIG. 5 is an opposite end elevational view of the medical tensioning device of FIG. 1;

FIG. 6 is top plan view of the medical tensioning device of FIG. 1; and,

FIG. 7 is a bottom plan view of the medical tensioning device of FIG. 1.
